US0D1029171S

(12) **United States Design Patent** (10) **Patent No.:** **US D1,029,171 S**
(45) **Date of Patent:** **** May 28, 2024**

(54) **FIREARM GRIP**

(71) Applicant: **Springfield, Inc.**, Geneseo, IL (US)

(72) Inventors: **Nathan A. Brinkmeyer**, Le Claire, IA (US); **Stephen H. McKelvain**, Geneseo, IL (US); **Peter J. Leach**, Davenport, IA (US)

(73) Assignee: **Springfield, Inc.**, Geneseo, IL (US)

(**) Term: **15 Years**

(21) Appl. No.: **29/851,452**

(22) Filed: **Aug. 29, 2022**

(51) **LOC (14) Cl. 22-01**

(52) **U.S. Cl.**

USPC **D22/104**; D22/108

(58) **Field of Classification Search**

USPC D22/100, 103, 104, 105, 108, 199; D21/567, 570, 573, 574, 575

CPC .. F41A 3/66; F41A 11/00; F41C 23/10; F41C 3/00; F41C 7/00

See application file for complete search history.

(57) **CLAIM**

The ornamental design for firearm grip, as shown and described.

DESCRIPTION

FIG. 1 is a right, front, perspective view of the firearm grip showing our new design;

FIG. 2 is a right, rear, perspective view thereof;

FIG. 3 is a right side view thereof;

FIG. 4 is a left side view thereof;

FIG. 5 is a top view thereof;

FIG. 6 is a bottom view thereof;

FIG. 7 is a front view thereof; and,

FIG. 8 is a rear view thereof.

The evenly broken lines in the drawings disclose unclaimed portions of the firearm grip only and form no part of the claimed design; the dash-dot broken lines represent indeterminate length and form no part of the claimed design. The appearance of any portion of the firearm grip between the dash-dot broken lines from no part of the claimed design.

1 Claim, 6 Drawing Sheets
